JOHN A. KELLY, OF BROOKLYN, NEW YORK.

PROCESS OF MAKING SHOES.

Application filed September 9, 1920, Serial No. 409,225. Renewed May 3, 1924.

This invention is a process of making shoes wherein provision is made of increased security of attachment between the upper and the outsole, as a result of which the seam 5 will not pull away from the upper.

According to this invention, the procedure involves the step of positioning a stay in such relation to a last that the margin of an upper when lasted will overlap the stay, 10 thereafter attaching the margin of the upper to the stay as by stitching, cementing or stapling, then trimming the margin of the upper, placing an outsole upon the upper as usual, and finally stitching the outsole to 15 the upper and the stay so that the stitches pass through the stay as well as through the upper and the outsole.

In a preferred mode of procedure, the stay is connected or attached to a temporary insole by any one of several known means of 20 attachment commonly used in the art of making shoes, such as by cementing, stapling or by a chain stitch seam, thus providing for the ready disengagement between the said 25 temporary insole and the stay when the insole is to be dislodged or withdrawn from the shoe. Said stay is composed of any material suitable for the purpose, such as leather or fabric, and it consists of one or 30 more narrow flat pieces of material cut or shaped to follow the outline of the last at the forepart thereof.

Other features and advantages of the invention will appear from the following description taken in connection with the drawings, wherein—

Figure 1 is a plan view of a temporary insole with the stay attached thereto in a suitable manner as by a chain stitch.

Figure 2 is a plan view of the upper lasted over a temporary insole and a permanent shank piece, said upper being stapled to the stay positioned beneath the lasted upper.

Figure 3 is a plan view of the parts shown in Figure 2 after trimming the margin of the upper.

Figures 4 and 5 are vertical cross sectional views on the lines 4—4 and 5—5 respectively of Figure 3.

Figure 6 is a cross section through the shoe after stitching the outsole to the upper and the stay, the last having been previously removed, said view showing the operation of pulling out the chain stitch preliminarily to the step of dislodging the temporary insole.

Figure 7 is a cross section through the

shank portion of the shoe produced by my invention.

Figure 8 is a vertical longitudinal section through the upper and outsole after attachment, showing the steps of pulling out the chain stitch to detach the stay from the temporary insole and the dislodgment of such temporary insole from its position within the upper.

Figure 9 is a cross section through another form of the stay, in which form said stay is composed of two lapping pieces of material to one of which the upper is stapled, whereas the other piece overlaps the stapled edge of the first piece and the margin of the upper so that the line of staples is covered by a layer of material in order to afford a smooth surface within the shoe and thus prevent the staples from hurting the foot when the shoe is worn.

The temporary insole A is composed of a suitable flexible material, such as leather, fabric, etc., its shape and dimensions conforming approximately to the last. To this insole is detachably attached a stay B constituting an essential feature of the invention, said stay being composed of leather, fabric or other material suitable for the purpose. The stay is a thin flat piece of material conforming to the marginal contour of the insole, upon which the stay is positioned for one edge thereof to extend beyond the edge of said temporary insole. Said stay is attached to the insole by a temporary fastening, the same being shown as a chain stitch b, although the stay may be cemented, pasted, stapled or otherwise attached so as to leave its edges free. As shown the seam b passes through the middle portion of the stay B and the insole near the edge of the latter, both edges of the stay B being unattached and free.

C is a permanent shank piece, the same being provided within the edges thereof with a channel c producing a lip c'.

In carrying out the invention, the temporary insole is imposed upon a suitable last D' upon which said insole is retained temporarily by the usual lasting tacks d, the shank piece C being also imposed upon said last for the fore end of the shank to meet or lap the rear end of the temporary insole, see Figure 3.

The upper D is now lasted in the usual manner, the marginal portion d' being drawn over the last so as to have a substantial por-

tion of said margin d' extend over the temporary insole and the stay B, the lasted upper being held by lasting tacks d^2 , see Figure 2.

When using a temporary insole intended 5 to be dislodged from the shoe in the process of completing it, I use suitable tacks d^2 in the operation of temporarily fastening the upper so as to retain the parts in the desired relation.

10 Having lasted the upper with respect to the temporary insole A and the permanent shank piece C, I next proceed to fasten said upper to the stay B and the shank piece C, for which purpose it is desirable to employ a line of 15 staples E, shown in Figures 2 and 3, or by stitching or cementing. Along the shank piece the staples pass through the upper and the lip c' , see Figures 5 and 7, but along the temporary insole adjacent the margin thereof, the staples do not enter or pass through said insole but on the contrary the staples do pass through the upper and the stay B at the inner free marginal portion of said stay, see Figure 4.

25 It will be noted that I reserve the right to attach the margin of the upper D to the stay B by stitching or cementing the specified parts in fixed relation to each other. Assuming that it is desirable to staple the upper to 30 the stay, as heretofore described, and that for this purpose a stapling machine is used which embodies an anvil adapted to be inserted below the infolded upper margin and below one edge portion of the stay for the purpose of 35 clenching the staples, then the operator should so manipulate the upper with respect to the tacks d^2 that the upper and the stay are stapled in the intervals between the tacks, and if required to apply the staples close together for the full length of the upper margin as indicated in Figure 2, then and in that event the tacks d^2 should be temporarily withdrawn and reinserted as and when necessary. In any event, the attachment of the 40 upper by stapling to the stay can be performed in a manner sufficient to retain the upper in the required relation to the stay and the insole.

The upper having been stapled or otherwise secured to the shank piece and to the stay, 45 the upper is trimmed by cutting away the excess or surplus material shown in Figure 2, the line of the trim or cut being intermediate the series of lasting tacks d^2 and the series of 50 staples E so that the upper is trimmed close to the row of staples E so as to present a smooth appearance, and such trimming operation being performed advantageously while the whole surface is exposed to ready access 55 as shown in Figure 2, so that when trimmed the upper presents the smooth and trim appearance of Figure 3. At this stage, it may be 60 desirable to pull out the lasting tacks d d^2 and to remove the trimmed upper margin from 65 the insole so as to make provision for the ap-

plication and attachment of the outsole; but in some circumstances I may use short tacks d^2 and allow the trimmed upper margin to remain attached to the insole during the attachment of the outsole, whereby the tacks d^2 70 and the trimmed upper margin may be withdrawn with the insole when the latter is dislodged from the shoe, it being apparent that when the last is removed and the outsole is applied the insole is free to give inwardly 75 under the pressure of tacks d^2 and the trimmed upper margin.

In this connection it will be noted that in stapling the upper to the stay B, the last and the upper are manipulated by the operator 80 so that the usual anvil of the stapling machine will pass between the tacks d^2 and into position with respect to the stay for the purpose of clenching the staples in the usual manner.

An outsole F is now placed upon the upper, 85 and the last having been removed, said outsole is attached by stitching the same to the upper and to the stay, the seam f passing through said stay, the upper and the outsole, along the forepart of the upper, see Figure 90 6, and said seam f passing through the shank piece C, the upper and the shank portion of the outsole, see Figure 7.

It will be seen that at the forepart of the 95 shoe to be produced the upper and the outsole are fastened in a permanent manner to the stay B by the seam f , and that this stay B is temporarily held on the temporary insole A by a chain stitch b or its equivalent. It is now desirable to dislodge the temporary insole, for which purpose it becomes necessary to pull out the thread of seam b in order to 100 detach the temporary insole A from the permanently attached stay B, the operation of so pulling out the thread of seam b being indicated in Figures 6 and 8, after which the temporary insole A is gripped and pulled out of the upper, at which time the trimmed upper margin and the lasting tacks d^2 may be 105 also be removed from the upper by the operation of dislodging the temporary insole.

As indicated in Figures 6 and 8, the outsole F is provided in one face thereof with an undercut or channel g in which lies the lasted and trimmed margin of the upper and the narrow stay so that the inner surface of the resulting shoe remains in a smooth condition after the dislodgment of the temporary insole. In this connection it may be stated that in channeling the outsole to produce the channel or undercut g , I may so conduct the channeling operation by the aid of suitable tools, machinery, or other appliances, that the cut out portion or excised material constitutes the stay B, the same being utilized in the process 115 of producing the shoe.

The stay B is an important feature of my 120 invention, the stay affording means for stapling the upper without attaching said upper to the temporary insole during the operations 125 130.

of making the shoe, and said stay affording a secure hold for the permanent seam *f*, whereby the seam is precluded from pulling out of or through the upper, producing an improved 5 article of foot wear.

The dislodgment of the temporary insole from the upper exposes the stay *B* on the inner face of the outsole and exposes also the row of staples by which the inner margin of 10 the stay is attached to the upper. It may be and sometimes is desirable to conceal and protect the staples from contact with the wearer's foot, and in this contingency I may employ a stay composed of two pieces of material *B* *B'* indicated in Figure 9. It will be understood that the double thickness (or two layer) stay *B*, *B'*, of Figure 9 is prepared prior to assemblage with and attachment to the temporary insole, the two layers *B*, *B'*, 15 being in lapping relation one to the other and with flush edges. Said double thickness stay, or two layer stay, is assembled with the temporary insole *A* in the identical manner as the single thickness stay of Figures 20 1, 2, 3 and 4, i. e., the multiple layer stay *B*, *B'*, is imposed upon the temporary insole for one edge of the multiple layer stay to extend beyond the edge of the temporary 25 insole, in the same way as the single thickness stay *B* of Figure 1, and thereafter the multiple layer stay *B*, *B'*, is attached to the temporary insole by a seam *b* or its equivalent, said seam *b*, as shown in Figure 1, passing through the two layers *B*, *B'*, of the multiple layer stay intermediate the edges thereof, and said seam *b* passing also through the temporary insole. The seam *b* thus operates to fasten the middle part of the multiple layer stay *B*, *B'*, of Figure 9, to the 30 temporary insole *A* of Figure 1 in the same manner as the single layer stay of Figures 2, 3 and 4 is attached to the insole, such middle stitching *b* operating to fasten the multiple layer stay to the insole in a way to leave the 35 edges of the two layers *B*, *B'*, free and unattached.

When lasting the upper, the temporary insole with the multiple layer stay is imposed on a last and tacked thereto as described, and 40 the upper is lasted for the marginal part of the upper to be drawn around the edges and over the double layer stay. To fasten the upper to the stay, it is preferred to staple said upper to one layer only of the multiple 45 layer stay, and in this operation the anvil of a stapling machine is positioned, by the proper manipulation of the shoe in the hands of a skilled laster, to pass between the two layers *B*, *B'*, of the stay, whereby the layer 50 *B'* is stapled to the upper, and hence the staples do not pass through the part *B* of said stay. After lasting, the outsole is sewed to the upper and the two part stay, the seam *f* passing through the outsole, the upper and 55 the two parts *B* *B'* of the stay, see Figure 9.

Upon dislodging the temporary insole as described, the two part stay remains attached to the upper and the outsole, constituting a permanent part of the shoe, one layer of said stay being stapled to the upper and the 70 other layer of the stay covering the row of staples so as to protect the wearer's foot from possible injury by the staples.

From the foregoing description taken in connection with the drawings it will be noted 75 that in my invention I provide a two part insole, whereof the stay *B* of Figures 1, 2, 3, 4, 6 and 8 constitutes a marginal insole part, and the layer *A*, termed herein the temporary insole, of said Figures 1, 2, 3, 4, 6 80 and 8 constitutes the other insole part, the two said parts *AB* being prepared as a step in the process prior to the assemblage of the components of the shoe. These two parts *AB* of my insole are in separable relation one 85 to the other, and in the procedure as herein disclosed, the marginal insole part *B* is united with the upper and the outsole so that said part *B* becomes a unitary part of the resulting shoe, whereas the other part *A* (herein 90 designated the temporary insole) is dislodged by pulling it out of the upper at a certain stage in the procedure, all as hereinbefore disclosed.

The article resulting from the making of 95 shoes in accordance with my process herein disclosed is not claimed in this application, said article constituting the subject matter of my Patent No. 1,593,264, patented July 20, 1926.

Having thus fully described the invention, what I claim as new and desire to secure by Letters Patent is:

1. In the art of making shoes, the process which consists in attaching a stay to a temporary insole, imposing said attached stay and insole upon a last, lasting an upper into lapping relation to said stay, fastening the upper to the stay, said fastening between stay and upper being free from the insole, 105 trimming the upper, and dislodging said insole from the upper.

2. In the art of making shoes, the process which consists in assembling a narrow stay in a desired relation to a last, lasting an 110 upper into lapping relation to the stay, temporarily fastening the upper to the last by lasting tacks, stapling the stay and the upper together on a line adjacent the inner edge of the stay, removing excess material by trimming the upper in a line intermediate the lasting tacks and the staples uniting the stay and the upper, and attaching an outsole to the upper and the stay.

3. In the art of making shoes, the process 125 which consists in attaching a stay to the marginal portion of a temporary insole, imposing said insole with the attached stay upon a last, lasting an upper, attaching said upper to said stay, stitching an outsole by a seam which 130

- passes through the upper and the stay, and removing the insole from the upper, whereby the stay remains attached to the upper and to the outsole.
5. 4. In the art of making shoes, the process which consists in attaching a stay to the marginal portion of a temporary insole, imposing said insole with the attached stay upon a last, lasting an upper, fastening the stay 70 to the upper adjacent the free marginal portion of said upper, trimming the free margin of the upper along a line adjacent the attachment of the stay to said upper, sewing an outsole to the upper by a seam which passes 75 through the stay but is free from the insole, and dislodging the insole from the upper, leaving the stay attached to the upper and the outsole.
5. In the art of making shoes, the process 80 which consists in attaching a relatively narrow stay to the marginal portion of a temporary insole, the edge portions of said stay being unattached and free, imposing said insole with the attached stay upon a last, lasting 85 an upper, fastening the stay along its free inner margin to the upper adjacent the free edge of said upper, trimming the upper along a line adjacent the attachment of said stay to said upper, stitching an outsole by a seam 90 which passes through the upper and the stay, and dislodging the insole from said upper.
6. In the art of making shoes, the process 95 which consists in attaching a relatively narrow stay to a temporary insole, lasting an upper and attaching the margin thereof to said insole, attaching the upper to the stay independently of the attaching of the upper to the insole, imposing an outsole on the upper, attaching the outsole and the upper to the 100 stay separately from the aforesaid attachment of the upper and stay, and removing the insole from the upper.
7. In the art of making shoes, the process 105 which consists in attaching a stay to a temporary insole, lasting an upper, fastening the upper to said stay, imposing an outsole upon the upper, fastening the outsole and the upper to said stay independently of the aforesaid attachment of the upper and stay, and removing the 110 insole from the upper.
8. In the art of making shoes, the process 115 which consists in attaching a stay to a temporary insole, lasting an upper, attaching said upper and stay by a permanent line of fastenings, imposing an outsole upon the upper, attaching said outsole and the upper to the stay by a second line of permanent fastenings extending substantially parallel to the first named line of fastenings, and removing the 120 insole from the upper while allowing the stay to remain attached to the upper and the outsole.
9. In the art of making shoes, the process 125 which consists in assembling a relatively narrow stay to the marginal portion of a tem- porary insole, attaching the stay to said insole on a line to leave unattached a marginal portion of said stay, imposing the insole with its attached stay upon a last, lasting an upper, securing the stay along the unattached 130 free margin thereof to said upper on a line adjacent the free margin of the upper, assembling an outsole relatively to the upper, fastening the outsole to the upper and to the stay, and dislodging the insole from the upper, thereby leaving the stay attached to the upper and to the outsole by two lines of fastenings.
10. In the art of making shoes, the process 135 which consists in assembling a relatively narrow stay to the marginal portion of a temporary insole, temporarily attaching the stay to the insole by a chain stitch seam so as to leave free an inner marginal portion of the stay, imposing the insole with the attached 140 stay on a last, lasting an upper, stapling the free edge of the stay to the upper along a line adjacent the free marginal portion of said upper, trimming the upper, assembling an outsole relatively to the upper, stitching the outsole by a seam which passes through the upper and the stay, and dislodging the insole from the upper.
11. In the art of making shoes, the process 145 which consists in assembling a plurality of layers of relatively narrow stay material with respect to the marginal portion of a temporary insole, fastening said layers of stay material to said insole, imposing said insole with the attached stay upon a last, lasting an upper, attaching one layer of the stay material to the upper, stitching an outsole by a seam which passes through the upper and both 150 layers of stay material, and dislodging the insole from the upper, leaving both layers of stay material attached to the upper and outsole and with one layer of said stay material covering the line of fastening by which the upper is fastened to the stay material independently of the seam.
12. In the art of making shoes, the process 155 which consists in attaching a stay of relatively narrow material to a temporary insole, assembling said insole with the attached stay and with a shank piece in a desired relation to a last, lasting an upper, attaching said upper to the stay and the shank piece by a line of fastenings extending through the upper and the stay and also extending through the upper and a lip provided at the shank piece, stitching an outsole to the upper, the shank piece and the stay, and dislodging the insole from the upper, leaving the stay and the shank piece attached to the upper and the outsole.
13. In the art of making shoes, the process 160 which consists in attaching a stay of relatively narrow material to a temporary insole, providing a shank piece with a channel and a lip, assembling the insole and the shank 165

piece in a desired relation to a last, lasting an upper, stapling the upper to the stay and the lip of the shank piece so as to attach said upper independently of said insole, sewing 5 an outsole to the upper, the stay and the shank piece, and dislodging the insole from its position within the upper.

14. In the art of making shoes, the process which consists in channeling an outsole to exercise therefrom a narrow strip of material adapted to serve as a stay, temporarily attaching said stay to a temporary insole along the marginal portion thereof, imposing said insole with the attached stay upon a last, 15 lasting an upper, fastening the upper to the stay adjacent a marginal portion of said upper, assembling the channeled outsole relatively to the upper, attaching the outsole to the upper by a seam which passes through 20 said stay, and dislodging the temporary insole from said upper.

15. In the art of making shoes, the process which consists in providing a two-part insole, one part of which is a marginal part separable

from the other part of said insole, imposing 25 said two-part insole upon a last, lasting an upper into lapping relation to the marginal part of said insole, uniting the upper to said marginal part of the insole whereby the said marginal part is unitary with the resulting 30 shoe, and dislodging the other part of said insole from the upper.

16. In the art of making shoes, the process which consists in providing a two-part insole the parts of which are separable one from 35 the other and one of which parts is in marginal relation to the other part, imposing said two-part insole upon a last, lasting an upper into lapping relation to the marginal part of the insole, fastening the marginal part of the 40 upper to the marginal insole part whereby said marginal insole part is unitary with the resulting shoe, and dislodging the other part of said insole from the upper.

In testimony whereof I have signed my 45 name hereto this 2nd day of September, 1920.

JOHN A. KELLY.
